(57) **CLAIM**

The ornamental design for a pet toy, as shown and described.

DESCRIPTION

FIG. 1 is a top, rear, right side perspective view of a pet toy showing our new design;

FIG. 2 is a bottom, front, left side perspective view thereof;

FIG. 3 is a top plan view thereof;

FIG. 4 is a bottom plan view thereof;

FIG. 5 is a rear side view thereof;

FIG. 6 is a front side view thereof;

FIG. 7 is a left side view thereof;

FIG. 8 is a right side view thereof;

FIG. 9 is a cross sectional view thereof along the line 9-9 identified in FIG. 3;

FIG. 10 is a cross sectional view thereof along the line 10-10 identified in FIG. 3;

FIG. 11 is a front, top, right side perspective view thereof in an alternative environment; and,

FIG. 12 is a top plan view thereof in an alternative environment.

The broken lines in the drawings depict portions that represent unclaimed environment and form no part of the claimed design. The dot-dash lines are boundary lines that define the bounds of the claimed design and form no part thereof.
